FIG. 2

FIG. 1

FIG. 3

FIG. 4

FIG. 5

FIG. 1 is a perspective view of a combined hammer attachment and file showing my new design;

FIG. 2 is a perspective view thereof with the file element removed for use with a conventional hammer;

FIG. 3 is a top plan view thereof with the file element removed for ease of illustration;

FIG. 4 is a side elevational view thereof with the file element removed for ease of illustration; and

FIG. 5 is a side elevational view thereof with the file element removed for ease of illustration as seen from the side opposite the view of FIG. 4.

The broken line showing of a conventional hammer in FIG. 2 is for illustrative purposes only.

I claim:

The ornamental design for a combined hammer attachment and file, substantially as shown and described.
